ATTORNEY

UNITED STATES PATENT OFFICE.

ROBERT THOMPSON, OF JERSEY CITY, NEW JERSEY.

GAS-BURNER.

1,303,615.

Specification of Letters Patent. Patented May 13, 1919.

Application filed November 24, 1917. Serial No. 203,742.

To all whom it may concern:

Be it known that I, ROBERT THOMPSON, a citizen of the United States, residing at Jersey City, in the county of Hudson and 5 State of New Jersey, have invented certain new and useful Improvements in Gas-Burners, of which the following is a specification.

This invention relates to gas burners for heating or cooking stoves.

10 The main object of the invention is to provide a burner of this character so constructed that a light may be used in connection therewith and yet occupy a minimum amount of space, one coupling operating to 15 effect a connection with the supply pipe of both the stove burner and that for supplying light.

Another object is to provide an improved form of stove burner whereby a maximum 20 amount of heat may be obtained with a minimum consumption of gas and in which the heating area is largely increased without increasing the consumption of gas.

With the foregoing and other objects in 25 view, which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

35 In the accompanying drawings:

Figure 1 represents a top plan view of a burner constructed in accordance with this invention, and

40 Fig. 2 represents a transverse vertical section thereof.

In the embodiment illustrated a burner is shown adapted for connection with any suitable source of gas supply, a pipe 1 being here shown provided with an annular 45 flange or shoulder 2 on which the burner is designed to be supported.

The burner constituting this invention 50 comprises a substantially frusto-conical hollow gas tube 10 having means at its lower end for supporting it on the pipe 1 in a manner hereinafter to be described. This frusto-conical casing carries at its upper 55 end the burner proper 11 which is here shown in the form of a circular casing including a top 12 and bottom 13 spaced a suitable distance from each other to form

a gas receiving chamber, the gas being directed thereto from the tube 10 as is shown clearly in Fig. 2. The bottom 13 may be secured to the upper end of the tube 10 in any suitable manner, being here shown crimped in engagement therewith and an opening 14 is provided in one side wall of the burner casing for a purpose presently to be described. 65

Arranged around the top or upper face 12 of the burner adjacent the perimeter thereof is a plurality of spaced gas discharge apertures 15 which may be disposed at any suitable distance from each other 70 in a manner common with burners of this character. Opening through the casing 11 are a plurality of air drum tubes 16, five being here shown arranged in a circle, although obviously they may be disposed in 75 any other desired manner. Around the upper end of each of these tubes 16 are a plurality of gas discharge apertures 17, the gas passing therethrough being mixed with air admitted through the lower ends of the 80 tubes so that a mixture is provided which will result in a maximum amount of heat being produced with a minimum consumption of gas.

A gas pipe 3 extends upwardly through 85 the tubular member 10 and has an elbow coupling 4 at its upper end which connects an arm 5 therewith, said arm extending radially through the casing 11 and out through the opening 14 thereof where it is 90 provided with a gas jet 6, the supply of gas to said jet being controlled by the usual valve or cock 7. This gas jet may be disposed at any suitable or desired distance 95 relatively to the burner casing 11, the object being to supply light to said burner during the cooking operation.

A branch pipe 8 leads from the pipe 3, being connected therewith by a T-coupling 9 and is provided with a discharge nozzle 18 100 controlled by the usual valve 19 having an actuating handle 20 extending through the side wall of the tubular member 10 so that the gas passing through said pipe 8 may be turned on or cut off at the will of the operator. It is understood that the gas to the burner casing 11 is supplied through this branch pipe 8 and it will thus be obvious 105 that the burner may be supplied with gas independently of the gas jet 6 and vice versa. 110 By so positioning the gas supply pipe 3 which supplies both the burner and the gas

jet, a minimum amount of space will be occupied and the device will be rendered compact and may be easily removed and connected with any other pipe at any point desired.

5 The depending frusto conical tube 10 has an outwardly projecting annular flange 21 at its lower end around which is crimped an apertured plate 22 and an outer apertured plate 23 is arranged over said plate 22 and adapted to turn thereon for controlling the amount of air admitted to the casing.

10 It will thus be seen that the head plate or crown of the burner which is formed by the top 12 of the casing 11 will, when constructed as above described, emit a great number of small jets of gas which mingle with the air passing upward through the tube 16 and thus produce a maximum heating effect 20 and this plate when so constructed, presents a large heating area so that large vessels may be used in connection therewith as well as small ones.

25 From the foregoing description, taken in connection with the accompanying drawings, the advantages of the construction and of the method of operation will be readily apparent to those skilled in the art to which 30 the invention appertains and while I have described the principle of operation of the invention together with the device which I now consider to be the best embodiment thereof, I desire to have it understood that 35 the device shown is merely illustrative and that such changes may be made as are within the scope of the claimed invention.

I claim:

1. A hollow stove burner having a depending casing communicating therewith, a gas supply pipe extending through said casing and projecting through one side wall of the burner, a gas jet mounted on said projecting pipe end, and a valve controlled 45 branch pipe opening into said casing for supplying gas to the burner.

2. A hollow stove burner having a depending casing communicating therewith, a gas supply pipe extending through said casing and projecting through one side wall of the burner, a gas jet mounted on said projecting pipe end, and a valve controlled 50

branch pipe opening into said casing for supplying gas to the burner, said burner having a plurality of tubes opening vertically therethrough with discharge openings at their upper ends for the passage of gas, air being admitted through the bottom of said tubes.

55

3. A burner comprising a hollow casing 60 having apertures for the passage of gas therefrom, and provided with a depending tubular member communicating therewith, a gas pipe extending through said tubular member and through said casing with a gas 65 jet therein outside said casing, a valve controlled branch pipe opening into said tubular member for supplying gas to the burner, valve controlled means for supplying air to said tubular member, and a control valve for 70 said gas jet.

75

4. A stove burner comprising a circular casing having a plurality of gas discharge apertures arranged around its upper face adjacent its perimeter, a plurality of tubes 80 extending vertically through said casing and having openings around their upper ends communicating with the interior of the casing, and means for supplying gas to said casing.

85

5. A stove burner comprising a circular casing having a plurality of gas discharge apertures arranged around its upper face adjacent its perimeter, a plurality of tubes 90 extending vertically through said casing and having openings around their upper ends communicating with the interior of the casing, a tubular member depending from said casing, a gas pipe extending up through said tubular member and when laterally 95 through said casing projecting beyond the outer face thereof, a valve controlled gas jet carried by said projecting pipe end adjacent the casing to provide light for the burner, and a valve controlled branch pipe opening into said depending tubular member for supplying gas to the casing.

95

In testimony whereof I affix my signature in presence of two witnesses.

ROBERT THOMPSON.
